VERTICAL LIFT BRIDGE

Taneyoshi Sakamoto, Tokyo, Japan

Application November 11, 1933, Serial No. 697,604

4 Claims. (Cl. 14—42)

This invention relates to an improvement in vertical lift bridges having a one side drive for raising and lowering the span thereof, and particularly that type wherein an auxiliary counter-weight is included adjacent to one end of the span for assisting the main weights to fully counter-balance the weight of the span and facilitate raising and lowering the same.

The main object of my invention is to provide a lift bridge of the type indicated wherein the span may be raised and lowered without danger of tilting, by means of a single unit of hoisting machinery installed in one of the hoisting towers of said bridge, thus reducing the cost of installation and upkeep to a minimum.

Other objects and the various advantages inherent in the structure and operation of my invention will appear more fully in detail as this specification proceeds.

In the accompanying drawing forming part hereof, Figure 1 is a side elevation of a vertical lift bridge made according to the invention and embodying its salient features in practical form.

Figure 2 is a modification of the invention with reference to the arrangement of one of the cables thereof.

Figure 3 is a diagrammatic view of the operating parts of Figure 1 in a drawn out form to more fully illustrate the relations of the parts as well as their general arrangement and operation.

Throughout the views, the same reference numerals indicate the same or like parts.

In vertical lift bridges without overhead fixed span between the tops of the towers, it has heretofore been the usual practice to place the operating machinery on the movable span so that the total weight of the operating machinery would be carried on the movable span, resulting in a greater load for the span and consequently, a greater load for the operating machinery and which, in turn, would result in the increased cost of the structure as compared with a bridge with no operating machinery on the movable span.

In another type of vertical lift bridge also without any overhead fixed span, the operating machinery is placed in the tower or on the foundation on both sides of the movable span in order to avoid adding the dead weight of the machinery to the movable span. Naturally, such arrangement would not only increase the cost of the operating machinery but also introduce certain difficulties in operating the two units of the operating machinery in exact synchronism so that the span may be lifted or lowered in an exactly balanced condition. It is customary in such a

type of operating arrangement, to provide special motors equipped with synchronized speed regulating devices.

With the foregoing objects in view, and particularly in order to obviate the mentioned disadvantages, the present invention has been introduced in order to provide a simple and effective means for easily operating the span of a lift bridge.

Referring again to the drawing, in Figure 1 the vertical guide towers 1 and 2 have a vertically movable span 3 disposed between the same in such manner as to be guided by said towers during raising or lowering of said span. A supporting cable 4 is anchored at 5 to the upper portion of tower 1 upon the left side of Figure 1 and is passed beneath a roller 6 adjacent to the left end of span 3, said cable being passed directly to the right along the span over a second roller 7 at the right end of the span and thence downwardly into the foundation of the right hand tower 2 where it is anchored. In order to support the cable 4 along the distance from one of the sheaves or rollers 6 to the other at 7, a pair of supporting rollers 8 are arranged along in spaced positions to form cable guides or supports, the main guide sheaves being, of course, 6 and 7.

Inasmuch as both ends of cable 4 are anchored it is but necessary to support the right hand end of the span by means of a counterweight or an operating cable or any other suitable means and cable 4 will serve to maintain the span in horizontal position at any level of said span.

This function is in great part served by two counter-balancing weights 13 and 14, which together are intended to almost completely counter-balance the weight of the span, the weight 13 being connected by a cable 15 over a guide sheave 17 upon the left tower 1 to the left portion of the span, while weight 14 has a cable connecting the same over a sheave 18 upon the right hand tower 2 to the right end of the span. If weight 14 were sufficiently heavy to substantially counter-balance span 3 the counterweight 13 and its cable 15 would be practically superfluous as cable 4 would prevent the tilting of the span in a counter-clockwise direction in view of the location of said cable beneath sheave 6 and over sheave 7 of the span, but in practice it has been found to provide more smooth and reliable operation to divide the weight into two units 13 and 14 as shown.

A sub-counterweight of relatively smaller capacity than either weights 13 and 14 is suspended by a cable 20 which passes over sheave 21 down

to a winding drum 12 and from this drum the cable passes upwardly as an operating cable 9 over a sheave 11 and then over another sheave 10 upon tower 2 down to the right hand end of span 3. The operating cable 9 is secured to the winding drum 12 so that rotation of the latter will cause the sub-counterweight 19 to be raised or lowered and correspondingly the span 3 to be lowered or raised. The main counterweights 13 and 14 are so designed as to be somewhat deficient in weight to balance the total dead weight of the movable bridge span 3, while the sub-counterweight 19 is designed to complement the weight of said main counterweights sufficiently to fully counter-balance the span, with the result that the weights and the span will be in a truly balanced condition. In order to facilitate the guiding of the span by means of towers 1 and 2, the guide rollers 22, 22 are provided upon both ends 20 of said movable span.

From the foregoing it will be evident that if winding drum 12 is rotated in a clockwise direction the sub-counterweight 19 will be lowered while simultaneously serving to keep the cable 20 taut and also the hoisting cable 9, the latter in passing over sheaves 10 and 11 raising span 3 a corresponding distance to that through which weight 19 is lowered. Obviously, when the movable span 3 rises, both the main counterweights 13 and 14 will also descend simultaneously with sub-counterweight 19 because cables 15 and 16 passing over sheaves 17 and 18 upon the towers 1 and 2 will allow gravity to act upon said weights. It is likewise true that when the winding drum 35 12 is rotated by hand or by mechanical means in a counter-clockwise direction the span will descend between towers 1 and 2 because the winding cable 9 will be played out from drum 12 over sheaves 10 and 11 down to the span, while cable 40 20 will draw said counterweight 19 upwardly by direct mechanical force exerted by said winding drum, the force of gravity acting upon the span causing the same to overcome the combined weight of weights 13 and 14 because the effect of 45 the sub-counterweight 19 is thus removed by the deliberate operation of drum 12 by raising the latter weight.

In other words, the winding drum has the effect of allowing the sub-counterweight to be added 50 to the main counterweights so as to counter-balance the movable span by rotating said winding drum clockwise, when it will be found that only a trivial amount of power will be required to raise the span, while said drum if rotated in a 55 counterclockwise direction will immediately subtract the weight of the auxiliary counterweight 19 by directly and mechanically raising the same so that the superior weight of the span will cause the same to descend in exact correspondence with 60 the amount of cable played out from drum 12 during such counterclockwise rotation, the lowering of said span drawing the cables 15 and 16 from sheaves 17 and 18 downwardly with the 65 span and thus raising the main weights 13 and 14.

It will be obvious from the description of the 65 operation of the bridge as illustrated in Fig. 1 and also diagrammatically shown in Fig. 3 that in every position of the movable span 3 the same is counter-balanced by weights 13 and 14, together with the sub-counterweight 19, while the 70 operation of the winding drum 12 is interposed to allow the weight of the sub-counterweight to be added to or removed from association with the weight of the main counterweights 13 and 14, while the winding cable is constantly main- 75

tained in a taut condition by means of the sub-counterweight so that movement of the winding cable 9 and corresponding raising or lowering of the movable span 3 will be prompt and immediately responsive to rotation of drum 12 in either 5 direction.

In addition to the foregoing, it is also true that the described arrangement of the counterweights and their cables in the present type of lift bridge provides a greater safety of operation than that 10 of any conventional arrangement of counterweights, cables and the like in case the main hoisting cable should break. If said main cable should break, the sub-counterweight 19 would fall on the main counterweight 14 to add its own 15 weight thereto, so that the movable span would in any case be entirely in a balanced condition and could be brought to rest at any position along the guide rails of the guide towers.

In view of the fact that the winding drum is 20 disposed in one of the towers of the lift bridge and is thus in a position to control the movements of the movable span by means of the hoisting cable 9 as described, it is, of course, only necessary to have one unit of hoisting machinery 25 installed in said one tower for the purpose of operating the bridge and this is a decided advantage and economy. It is, of course, at no time necessary to install the hoisting machinery upon the span itself or in both of the towers or their 30 foundations but solely in one of the towers or in the foundation thereof by virtue of the presence of the sub-counterweight 19 and its connection with the hoisting cable and span 3.

In Figure 2 is shown a modification wherein the 35 auxiliary operating or supporting cables 4 and 4' are wound around a pair of drums 23 and 23' respectively, which are secured to individual ends of a horizontal shaft 24 journaled upon the side of the movable span 3. From these drums 23 40 and 23' the auxiliary operating or supporting cables 4 and 4' extend vertically upward and downward respectively, the cable portion 4 being fixed to the top of the tower 1 and the cable portion 4' to the foundation of tower 2. In this modification, instead of a portion of the cable 4 passing 45 along the span from one end to the other over supports or guides 8, the shaft 24 forms the connecting link which provides the same relation between the ends of the cable and the ends 50 of the span and a similar control of the latter as the arrangement of cable 4, sheaves 6 and 7 and span 3 in Figure 1. In other respects the cables and counterweights, as well as the sub-counterweight and the operation on the whole, 55 is the same as before.

While I have shown and described but one or two forms of my invention and have not definitely detailed the construction of the towers and any other conventional parts, it is obvious 60 that any known practical construction may be used for building the same and manifestly, variations of my invention may be resorted to and parts may be used without others.

Having now fully described my invention, I 65 claim:

1. In a vertical lift bridge of the character described wherein the bridge is provided with a pair of spaced towers, a movable span disposed between said towers and having a roller at each end, 70 a cable fixed at one end to the upper portion of one tower and passing beneath the roller on the movable span adjacent to said tower and over the roller at the other end of the span and having the other end fixed adjacent to the lower por- 75

tion of the second tower at said other end of said span, and at least one counterbalancing cable secured to said other end of the span and passed over a sheave upon said second tower, the feature 5 of having a counterbalancing weight upon said counterbalancing cable which is insufficient to counterbalance the dead weight of said span, a hoisting drum, a hoisting cable also secured to said other end of the span and passed over a 10 sheave upon said second tower and about said hoisting drum, and a sub-counterweight designed to complement said first counterweight in completely counterbalancing said span and suspended 15 upon the end of said hoisting cable which extends from said hoisting drum.

2. A vertical lift bridge according to claim 1, wherein the sub-counterweight is suspended in the second tower in a position above the counterbalancing weight upon the counterbalancing 20 cable in said tower in order to cause said sub-counterweight to drop and rest upon said counterweight in case the hoisting cable breaks.

3. A vertical lift bridge according to claim 1, wherein there are two counterbalancing weights 25 individually suspended upon cables connected to

both ends of the movable span, which two weights together are insufficient to counterbalance the dead weight of the span, and wherein the sub-counterweight supplements the weight of both said counterbalancing weights so that the aggregate weight of all three weights counterbalances the dead weight of the span. 5

4. A vertical lift bridge according to claim 1, wherein there are two counterbalancing weights individually suspended upon cables connected to 10 both ends of the movable span, which two weights together are insufficient to counterbalance the dead weight of the span, and wherein the sub-counterweight supplements the weight of both 15 said counterbalancing weights so that the aggregate weight of all three weights counterbalances the dead weight of the span, the sub-counterweight being suspended in the second tower in a position above the counterbalancing weight upon 20 the counterbalancing cable in said tower in order to cause said sub-counterweight to drop and rest upon said counterweight in case the hoisting cable breaks. 25
